PROCESS FOR REMOVING NAPHTHENIC ACIDS FROM HYDROCARBON OILS

Franz Rudolf Moser, Amsterdam, Netherlands,
assignor to Shell Development Company, San Francisco, Calif., a corporation of Delaware

No Drawing. Application December 24, 1937,
Serial No. 181,702. In the Netherlands January 4, 1937

7 Claims. (Cl. 196—36)

This invention relates to the removal of naphthenic acids from hydrocarbon oils by catalytic destruction of the latter at elevated temperatures, and in particular deals with the removal 5 of naphthenic acids from mineral lubricating oil distillates.

Hydrocarbon oils often contain considerable amounts of acidic components, which during the processing of the oils, particularly at elevated 10 temperatures, may cause severe corrosion of the treating equipment. Thus corrosion difficulties have been experienced, for instance, when distilling, with or without steam, relatively high boiling oils such as gas oil, Diesel fuel oils, lubricating oils, etc., containing free naphthenic acids 15 particularly if their acid numbers are high, for instance above 2. In order to overcome this difficulty various means have been employed, all of which, however, have certain disadvantages. 20 For instance it has been attempted to subject the oils to selective cracking at temperatures between about 315° to 400° C. in the liquid phase without a catalyst, whereby it was hoped the naphthenic acids would be decomposed to neutral compounds 25 and CO₂, while the hydrocarbon oils remained substantially uncracked. It was found that under these conditions some decomposition of naphthenic acids takes place, but it is slow and incomplete. Moreover, the corrosion during this 30 treatment may be severe and may persist in subsequent treatments.

Another method consisted of passing vapors of mineral oil containing naphthenic acids over alkaline earth metal oxide at temperatures of 35 about 200° C. to produce alkaline earth naphthenates, and heating subsequently the naphthenates so produced to about 400° C. to remove therefrom ketones and CO₂, thereby restoring the alkali earth oxide. This intermittent process 40 has the disadvantage that it requires frequent changes of temperatures of the reacting masses, which reduce the available operating time, make operating of the process on a large scale difficult, and raise operating expenses.

45 Other methods of removing naphthenic acids comprise distilling oils containing naphthenic acid for instance over caustic soda under conditions to retain the naphthenic acids in the alkaline-reacting residue in the form of a so-called soda asphalt, which, however, is a troublesome material of little use.

It is the purpose of this invention to provide a continuous method, whereby naphthenic acids contained in mineral oil can be eliminated quickly and substantially completely, without produc-

ing an undesirable residue and without materially decomposing or otherwise damaging the hydrocarbons with which the acids are associated.

I have discovered that naphthenic acids can be eliminated quickly and substantially completely in a single step operation from mineral oils containing them by conducting the oil, preferably in the vapor phase, at an elevated temperature, preferably above 250 to 300° C., if desired in the presence of steam and under conditions substantially to avoid cracking of the hydrocarbons, over a catalyst promoting the destruction of the carboxylic group or the conversion of the carboxylic group into a non-acidic group.

The reaction by which the naphthenic acids are eliminated is one of decomposition, free CO₂ and neutral compounds, presumably ketones and/or hydrocarbons being formed.

The catalysts suitable for the above purpose are known as catalysts for ketonic decomposition 20 or for decarboxylation, *vide e. g.*:

Sebatier: *Die Katalyse in der organischen Chemie*, 1927, page 253 et seq.

Ipatieff: *Catalytic Reactions at High Pressures and Temperatures*, 1936, page 121 et seq.

Bugge: *Industrie der Holzdestillationsprodukte*, 1927, pages 139, 143 et seq.

Hilditch and Hall: *Catalytic Processes in Applied Chemistry*, 2nd ed., page 258 et seq.

Ullmann: *Enzyklopädie der technischen Chemie*, 1928, I, page 111.

Such catalysts are, for instance, inorganic metal compounds, particularly the carbonates, the basic carbonates and the oxides of lithium and of the alkaline earth metals (Be, Mg, Ca, Sr and Ba); the oxides and corresponding salts of the rare earths, especially thorium oxide, iron, manganese, chromium, uranium, cadmium and zinc, are also effective to some extent. Of these, the carbonates of lithium and the alkaline earth metals, and particularly of the group of metals having combining weights below sodium, i. e. lithium, magnesium and calcium, are particularly effective.

Mixtures of several catalysts may be used, often to considerable advantage. For instance mixtures consisting predominantly of an alkali earth carbonate and a small amount of lithium carbonate prove to be very active. Thus a calcium carbonate catalyst containing 1% lithium carbonate may be almost as effective as lithium carbonate alone. Catalysts which have an acid character and especially those which contain a substantial amount of free mineral acid cannot be used for the process according to the inven-

tion; for the rest such catalysts are not known to be catalysts for ketonic decomposition.

The method of preparing the catalyst has usually a considerable influence on its activities. This 5 method has to be carried out in such a manner as to ensure a great porosity and consequently a large catalytic surface. For example, normal lime, either or not mixed with crude iron oxide, causes little or no decomposition of the acids, but 10 Ca oxide, which is very finely ground (e. g. grain size 30-40 A. S. T. M. sieve), is a suitable catalyst for the purpose described. Lithium carbonate and earth alkaline carbonates may be obtained from solutions of soluble salts by precipitation; or by 15 calcining or igniting their bicarbonates, or carboxylic acid salts which upon heating will decompose to form carbonates, in particular formates, acetates, oxalates and higher fatty acid salts, and naphthenates. Carbonates obtained by pyro- 20 genetic decomposition of organic salts are usually more efficient than the precipitated forms. Furthermore the degree and temperature of the heat treatment normally has a considerable influence. Thus between three calcium carbonates produced 25 by calcining the acetate in a closed furnace at 450° C., by igniting the acetate in contact with air in a crucible until gray and by igniting until completely white respectively, the relative efficiencies as measured by the length of the life of 30 each under a given set of conditions were 1 : 4 : 6, the higher figures indicating longer life. Analysis showed that all three catalysts consisted essentially of calcium carbonate, containing only small amounts of calcium oxide and the only 35 difference between the three catalysts apparently being in the surface structures.

Certain active metal carbonates tend to decompose materially under the conditions of my treatment to the oxides or basic carbonates 2nd 40 CO₂, particularly if steam is present as is usually the case when treating relatively heavy lubricating oil distillates. If desired, CO₂ may be added to the hydrocarbon vapors in such an amount that the partial pressure of the CO₂ in the vapor 45 phase is equal to or higher than equilibrium CO₂ pressure of the metal carbonate. In this way the decomposition of the carbonates into oxides or basic carbonates may be prevented, although in general the said decomposition does not influence 50 the working of the catalyst. The lithium, magnesium and calcium carbonates have a sufficiently low CO₂ pressure under the treating conditions, so that ordinarily no CO₂ need be added to the vapors, even in the presence of substantial 55 amounts of steam, the partial pressure of CO₂ in the vapors due to the decomposition of the naphthenic acids usually being sufficient to prevent a material decomposition of these carbonates.

Active catalysts may be used alone or deposited 60 on inert solid carriers, such as coke, tile, majolica, asbestos, graphite, porcelain, etc., and if desired, in combination with a variety of activators.

Suitable contact temperatures range from 65 about 300° C. to temperatures of incipient cracking or slightly above, i. e. about 475° C. Incipient cracking temperatures and rates of cracking at a given cracking temperature vary somewhat with the boiling range and the nature of the oil, as shown by Geniesse and Reuter in Industrial Engineering Chemistry 24 (1932), page 219 et seq. Exposure of the oil to temperatures above incipient cracking temperatures should be so limited 70 to avoid substantial cracking. In general treating temperatures should not exceed about 475° C. and are preferably below about 450° C.

The limited time available when treating at temperatures above incipient cracking is, however, more than sufficient to eliminate the largest portion of naphthenic acids contained in hydrocarbon oils. For instance, whereas at 450° C. it requires between 3 to 4 seconds to crack a gas oil to the extent of 1%, a contact time of $\frac{1}{25}$ second is usually sufficient at temperatures from 400° C. to 450° C. to remove 95% or more of the naphthenic acids in contact with an active carbonate catalyst. Since a longer time of contact results in a more complete removal, I may extend this time to several seconds, where this can be done without danger of cracking or otherwise adversely affecting the oil.

The following examples further illustrate my process:

A lubricating oil distillate containing naphthenic acids and having an acid number of 2, produced by distillation of Venezuelan crude oil, was 28 passed in the vapor phase at a pressure of 100 millimeters Hg and in the presence of steam over a catalyst consisting of granulated lithium carbonate. About 30 volumes liquid oil were thus contacted with 1 volume of catalyst per hour. 25 The calculated time of contact was $\frac{1}{25}$ second.

The treated oil vapors were condensed and small amounts of liberated gaseous CO₂ were separated from the liquid. The catalyst remained active until about 5 mols of naphthenic 30 acids per mol. of carbonate had been decomposed. After this the activity declined due to accumulation of carbon.

The condensed liquid oil had an acid number of about .1 and a distillation range and unsaturation substantially equal to that of the untreated oil.

When substituting in the above experiment sodium and potassium carbonates for the lithium carbonate, it was found that the lives of these 40 catalysts were only about $\frac{1}{20}$ of that of the lithium carbonate because of extensive sintering.

Certain forms of magnesium carbonate, such as those produced by calcining magnesium acetate, had relatively long life, which compared 45 favorably with those of lithium carbonate. However, under the conditions of the above experiments magnesium carbonate reduced the acid number of the oil to about .3 only, and a longer time of contact was necessary in order further to reduce the naphthenic acid content.

Calcium carbonate, particularly when obtained by ignition of calcium acetate under conditions to produce a pure white substance, analyzing as substantially pure calcium carbonate containing but small amounts of CaO, proved to be 55 very efficient, and had an active life comparing favorably with those of many forms of lithium carbonates. Also mixtures of calcined and precipitated calcium carbonates were very effective 60 though perhaps somewhat inferior to pure calcined calcium carbonate.

Addition of 1% lithium carbonate to a relatively poor calcium carbonate, which was obtained by calcining calcium acetate at 450° C. in 65 a closed furnace, and which had an active life of $\frac{1}{6}$ or less of the pure white carbonate described above, extended the life of the former 6 to 8 times. Moreover, its effectiveness was raised, so that without changing the conditions 70 of the treatment the acid value of the treated oil was reduced from .45 to .15 due to the addition of the lithium carbonate.

An unrefined Venezuelan lubricating oil distillate containing about 2% sulphur, with an acid 75

figure = 2 has been fed in the presence of 2.5% by weight of steam at 400° C. in the vapor phase over 10 cm.³ (=8.8 g.) of a lithium carbonate catalyst.

5 The catalyst had been obtained by compressing technical lithium carbonate to pills and reducing them to such a size of grain that they pass through A. S. T. M. sieve 30 and not through sieve 40. After heating to 400° C. the hollow 10 space of this catalyst was determined by filling a pycnometer with catalyst and weighing it, subsequently evacuating, introducing water and weighing once more. The amount of cm.³ water taken up, calculated from the increase in weight, 15 was looked upon as hollow space and amounted to 66.9%.

The average molecular weight of the oil was 370.80 g. (=100 cm.³) oil passed through per hour.

20 From these figures it can be calculated that the oil vapor remained in the catalyst for about $\frac{1}{15}$ sec.

The progress of the desulfurization and the de-acidification is illustrated by the following table:

Duration in hours	4	10	40	100	Blank (passed through apparatus without catalyst)
30 Acid figure.....	0.06	0.06	0.06	0.06	1.80
Sulphur content.....	2.19%	1.93%	1.92%	2.06%	2.08

35 The acid figure of the oil has, therefore, dropped from 2 to 0.06, this drop being maintained for 100 hours of use, whilst the sulphur content remains practically unchanged.

I claim as my invention:

1. In the process of removing naphthenic acids 40 from hydrocarbon oils containing same, the steps comprising contacting said oil in a heated vaporous condition at a temperature between 300° and 475° C. with lithium carbonate for a time sufficient to decompose a major portion of the naphthenic acids, thereby liberating CO₂, but insufficient substantially to crack the oil.

45 2. In the process of removing naphthenic acids from hydrocarbon oils containing same, the steps comprising contacting said oil in a heated vaporous condition at a temperature between 300° and 475° C. with a catalyst the active component 50 of which consists essentially of an alkali metal carbonate containing a small amount of lithium carbonate, for a time sufficient to decompose a major portion of the naphthenic acids, thereby liberating CO₂, but insufficient substantially to crack the oil.

55 3. In the process of removing naphthenic acids

from hydrocarbon oils containing same, the steps comprising contacting said oil in a heated vaporous condition at a temperature between 300° and 475° C. with a calcium catalyst comprising white calcium carbonate obtained by igniting calcium acetate, for a time sufficient to decompose a major portion of the naphthenic acids, thereby liberating CO₂, but insufficient substantially to crack the oil.

4. In the process of removing naphthenic acids 10 from a hydrocarbon oil containing same, the steps comprising contacting said oil in a heated vaporous condition at a temperature between 300° and 475° C. with an amount substantially less than the equivalent of said naphthenic acids 15 of a metal carbonate which is substantially stable under the conditions of the treatment, for a time sufficient to decompose a major portion of the naphthenic acids, thereby liberating gaseous CO₂, but insufficient substantially to crack the oil.

20 5. In the process of removing naphthenic acids from hydrocarbon oils containing the same, the steps comprising contacting said oil in a heated vaporous condition at a temperature between 300° and 475° C. with an amount substantially less 25 than the equivalent of said naphthenic acids of a catalyst whose active component consists essentially of the carbonate of an alkaline earth metal, for a time sufficient to decompose a major portion of the naphthenic acids, thereby liberating gaseous CO₂, but insufficient substantially to crack the oil.

30 6. In the process of removing naphthenic acids from hydrocarbon oils containing the same, the steps comprising contacting said oil in a heated vaporous condition at a temperature between 300° and 475° C. with a catalyst whose active component consists essentially of a carbonate of an alkali earth metal, for a time sufficient to decompose a major portion of the naphthenic acids, thereby liberating CO₂, but insufficient substantially to crack the oil, said carbonate having 40 been produced by igniting a salt of one of said metals and a carboxylic acid, which salt upon heating is converted to the carbonate.

45 7. In the process of removing naphthenic acids from hydrocarbon oils containing the same, the steps comprising contacting said oil in a heated vaporous condition at a temperature between 300° and 475° C. with a catalyst the active component of which consists essentially of an amount of calcium carbonate substantially less than the equivalent of said naphthenic acids, for a time sufficient to decompose a major portion of the naphthenic acids, thereby liberating gaseous CO₂, but insufficient substantially to crack the oil.

55 FRANZ RUDOLF MOSER.
